ATTORNEY'S

UNITED STATES PATENT OFFICE.

GEORGE ASHCOM BEALL, OF VELASCO, TEXAS.

DESIGN FOR A SUGAR-CANE HOOK.

SPECIFICATION forming part of Design No. 27,430, dated July 27, 1897.

Application filed May 5, 1897. Serial No. 635,266. Term of patent 14 years.

To all whom it may concern:

Be it known that I, GEORGE ASHCOM BEALL, a citizen of the United States, and a resident of Velasco, in the county of Brazoria and State of Texas, have invented and produced a new and original Design for a Sugar-Cane Hook, of which the following is a specification, reference being had to the accompanying drawings, forming a part thereof.

Figure 1 is a perspective view of a sugar-cane hook showing my new design. Fig. 2 is a plan view of the same. Fig. 3 is a side view thereof.

As shown in the drawings, the leading or material features of my design consist in the

straight shank having a bifurcated outer end, providing a pair of outwardly-branching and downwardly and inwardly curved hooks.

The sugar-cane hook in plan view is of Y shape, having incurved and outcurved prongs. 20

Having thus described my invention, what I claim as new, and desire to secure by Design Letters Patent, is—

The design for a sugar-cane hook substantially as herein shown and described.

GEORGE ASHCOM BEALL.
